The ornamental design for sharps container, as shown and described.

DESCRIPTION

FIG. 1 is a perspective view of a sharps container showing my new design;
 FIG. 2 is a perspective view shown with the closure element in a raised position;
 FIG. 3 is a top plan view thereof;
 FIG. 4 is a front elevational view thereof;
 FIG. 5 is a bottom plan view thereof;
 FIG. 6 is a rear elevational view thereof;
 FIG. 7 is a left side elevational view thereof;
 FIG. 8 is a right side elevational view thereof;
 FIG. 9 is a perspective view of a second modified embodiment;
 FIG. 10 is a perspective view shown with the closure element in a raised position;
 FIG. 11 is a top plan view shown with the closure in a closed position;
 FIG. 12 is a front elevational view thereof;
 FIG. 13 is a bottom plan view thereof;
 FIG. 14 is a rear elevational view thereof;
 FIG. 15 is a left side elevational view thereof; and,
 FIG. 16 is a right side elevational view thereof.
